UNITED STATES PATENT OFFICE.

ERNEST MILLER, OF NEW YORK, N. Y.

SAFETY CLASP.

Application filed March 7, 1925. Serial No. 13,813.

To all whom it may concern:

Be it known that I, ERNEST MILLER, a citizen of Switzerland, and resident of New York, in the county of New York and State 5 of New York, have invented certain new and useful Safety Clasps, of which the following is a specification.

This invention relates to improvements in safety-clips or clasps, and it is the principal 10 object of the invention to provide a clasp which is simple and inexpensive in its construction, and which will securely hold wallets, pocketbooks within the pocket of the wearer and will positively prevent extraction from the pocket by pick-pockets or 15 the like.

Another object of the invention is the provision of a safety-clasp or clip for securely holding together valuable papers, 20 bank notes or the like protecting them against abstraction.

A further object of the invention is the provision of a safety-clip which can be readily operated to clamp the wallet to the 25 flap or inner pocket seam, or one which may be safely put to many other uses, as for instance necktie clasp or the like.

A still further object of the invention is the provision of a safety clasp including a 30 plurality of interlocking clamp plates adapted to readily clasp and unclasp.

These and other objects and advantages of my invention will become more fully known, as the description thereof proceeds, 35 and will then be specifically defined in the appended claim.

In the accompanying drawing, forming a material part of this disclosure:

Fig. 1 is a front elevation of a clasp constructed according to the invention with the clamp plates in alignment for allowing an attachment of the clasp to an article.

Fig. 2 is a side elevation thereof.

Fig. 3 is a view similar to Figure 1, however with the clamp plates out of alignment for locking the clasp over an article and its support.

Fig. 4 is a side elevation thereof.

Fig. 5 is a side elevation of the clasp 50 showing the same in use.

The clasp comprises a plate 10 or member made preferably from spring metal having an opening 11 therein, and bent upon itself at its upper edge, as at 12, where it is 55 equipped with spaced reinforcing ribs 13

and 14 respectively on its outer face to form a shank 14' parallel to plate 10.

The inner end of shank 14' is then outwardly bent, as at 15, and then straight, to form a shoulder plate or abutment 16, 60 whereupon it is downwardly bent again, as at 17; the abutment 16 has the particular function to bring about the movement of the shanks toward and away from each other.

A clamp member or plate 18 is pivotally attached near its upper end, as at 19, to the bent shank 14' and is adapted to engage the outer face thereof.

This plate 18 has at its lower ends rearwardly and downwardly directed or extending fingers or elements 20 which are connected by a pin 21 having headed ends, while the lower edge of plate 18 is formed with knuckle-members 22 or the like corrugations.

On pin 21 are also pivotally secured the rearwardly directed fingers or elements 23, pointing upwardly from another clamp plate 24, the inner edge of which has also a plurality of rounded knuckle-members 25 adapted to engage into the spaces between the knuckles 22 in order to present a smooth outer face if the clasp is in the position shown in Figure 2.

The plate 24 is pivotally secured, intermediate its ends, as at 26, to the lower end of part 17.

The device operates as follows:

If it is desired to use the clasp for securing a wallet or the like article containing valuables within a coat pocket, the wallet is placed between member 10 and part 17, and the engagement between members 22 and 25 is broken as indicated in Figure 4, to hold the wallet in the clasp. When now the clasp and wallet are placed into a coat pocket, a pressure upon plates 18 and 24 through the lining 27 of the pocket, Figure 5, will close the clamp plates 18 and 24 so that the material of the pocket lining 27 will be securely gripped between members 22 and 25, and the clasp and wallet are thus securely held within the pocket against stealthy withdrawal. A slight pressure on the longer plate 24 will suffice to open the clasp and the clasp and wallet can then readily be removed from the pocket.

It is to be understood that the drawing represents only one, the preferred form of 110

my clasp and that such changes may be made in its construction and in the arrangement of the minor details thereof, as fall within the scope of the appended claim,
5 without departure from the spirit of my invention.

Having thus described my invention, what I claim as new, and desire to secure by Letters Patent is:

10. A safety-clasp of the class described, comprising a reinforced and perforated spring metal plate bent upon itself to form two parallel shanks connected by an upper bend, an inwardly extending loop or abutment formed in one of its shanks adapted to be brought closer to said other shank, a pair of clamp plates, a pin for pivotally securing and connecting the inner meeting edges

of said clamp plates, knuckle members interengaging, formed at said meeting edges, 20 above said pin, one of said clamp plates pivotally secured near its outer end to one of said shanks above the abutment formed therewith, and the other of said plates pivotally secured intermediate its ends to the 25 same shank and acting as an operating member to break the engagement between the inner meeting edges of both clamps for varying the distance between both shanks to allow a clasping of a wallet to an inner 30 coat pocket.

Signed at New York, in the county of New York and State of New York, this 4th day of March A. D. 1925.

ERNEST MILLER.
